UNITED STATES PATENT OFFICE

FREDERICK J. KISTNER, OF CINCINNATI, OHIO, ASSIGNOR TO THE J. A. FAY & EGAN COMPANY, OF CINCINNATI, OHIO, A CORPORATION OF WEST VIRGINIA

DESIGN FOR A DOWEL MACHINE

Application filed July 26, 1932. Serial No. 44,449. Term of patent 14 years.

To all whom it may concern:

Be it known that I, FREDERICK J. KISTNER, a citizen of the United States, residing at Cincinnati, in the county of Hamilton and State of Ohio, have invented a new, original, and ornamental Design for Dowel Machines, of which the following is a specification, reference being had to the accompanying drawing, forming part thereof.

Fig. 1 is a front perspective view of the

dowel machine the guide element being omitted from the lefthand side of the cutting head, and,

Fig. 2 is a rear elevation of the same shown on a greatly reduced scale.

I claim:

The ornamental design for a dowel machine, substantially as shown.

FREDERICK J. KISTNER.
